UNITED STATES PATENT OFFICE.

EDWARD P. THOMANDER, OF EPHRAIM, UTAH, ASSIGNOR OF ONE-HALF
TO HANS P. PETERSEN, OF EPHRAIM, UTAH.

SOAP AND TOWEL RACK.

No. 839,837.

Specification of Letters Patent.

Patented Dec. 25, 1906.

Application filed April 17, 1906. Serial No. 312,230.

To all whom it may concern:

Be it known that I, EDWARD P. THOMANDER, a citizen of the United States, residing at Ephraim city, in the county of Sanpete and State of Utah, have invented certain new and useful Improvements in Soap and Towel Racks; and I do declare the following to be a full, clear, and exact description of the invention, such as will enable others skilled in the art to which it appertains to make and use the same.

This invention relates to improvements in devices for holding soap and towels; and it consists of the novel construction, combination, and arrangement of devices hereinafter described and claimed.

One object of the invention is to provide a simple and practical device of this character which will support a cake of soap and a towel adjacent to a washbasin or stand within convenient reach of a user and at the same time concealed from view and out of the way.

Another object of the invention is to provide a device of this character which will be simple, durable, and comparatively inexpensive in construction and sanitary, economical, and convenient in use.

The above and other objects, which will appear as the nature of my invention is better understood, are accomplished by means of the construction illustrated in the accompanying drawings, in which—

Figure 1 is a front elevation of my improved soap and towel rack or supporting device, showing the casing broken away and a part of the spring-actuated winding-roller in section. Fig. 2 is a vertical sectional view taken on the plane indicated by the line 2 2 in Fig. 1; and Figs. 3 and 4 are detail views of the roller, showing two ways in which the towel may be removably secured thereon.

Referring to the drawings by numerals, 1 denotes a cake of soap and 2, a towel, which are supported by my improved rack or supporting device 3. The latter comprises a suitable base 4, upon which is mounted, beneath a hood or casing 5, a spring-actuated winding-roller 6 similar in construction to the usual self-winding curtain-shade roller. This roller 6 may be of any desired form and construction, and its pivots or trunnions are mounted in brackets 7, secured upon the front of the base board or plate 4, so that the roller is disposed horizontally in the casing or

hood 5 above its open bottom. Upon the 55 roller, adjacent to one of its ends, is secured a spool or drum 8, having secured to and wound upon it a cord or similar flexible connection 9, from which the cake of soap 1 is supported. Upon the outer or free end of the cord 9 is a 60 spring-holder 10, formed, preferably, by bending a piece of resilient wire, as shown in Fig. 1, to form inwardly spring-jaws 11, having inwardly-projecting spurs to enter the cake of soap. The towel 2, which rolls upon the 65 roller 6, may be attached thereto by any suitable means which would permit it to be readily removed. The attaching means shown in Figs. 2 and 3 of the drawings consists in forming in the roller a longitudinally-extending groove 12, in which the upper or inner end of the towel is clamped by a retaining-strip 13. The latter has one of its ends hinged, as at 14, and its opposite end secured to the roller by means of a catch 15. The 75 fastening means for the towel shown in Fig. 4 of the drawings comprises a longitudinally-extending metal strip or plate 15, secured upon the roller and having one of its side edges notched or cut to form spring-teeth 16, 80 beneath which the inner end of the towel is placed, so that it will be clamped upon the roller.

The operation and advantages of the invention will be readily understood from the 85 foregoing description, taken in connection with the accompanying drawings. It will be seen that the towel and the cord 9 will be normally wound upon the roller and spool so that both the towel and soap will be supported within the hood or casing 5, concealed from view and out of the way, but at the same time they may be readily lowered for use by pulling downwardly upon the towel or the cord. By operating either of the latter as 90 95 one does a window-shade the soap and towel may be supported at any desired elevation. By suspending the soap in this manner the necessity of a soap dish or holder is obviated and the soap is kept clean and dry and there 100 is practically no waste of it, as is so common in the ordinary soap dishes and trays. The device is of extremely simple and durable construction, so that it may be manufactured at a comparatively small cost and will last 105 indefinitely, and it is exceedingly convenient in operation. The casing 5 may be ornamented, if desired.

Various changes in the form, proportion, and the minor details of construction may be resorted to without departing from the principle or sacrificing any of the advantages of this invention as defined by the appended claims.

Having thus described my invention, what I claim as new, and desire to secure by Letters Patent, is—

- 10 1. The herein-described rack comprising the base having the brackets, the roller mounted in said brackets and having the spring to rotate the same in one direction, and the towel and soap-suspending cord attached to the roller and partly wound thereon, in such direction that when either is pulled against the tension of the spring to cause the same to become partly unwound from the roller, the latter will be revolved
- 15 2. and cause the other to be also unwound, so that both the towel and the soap-suspending

cord will be either wound or unwound simultaneously.

2. The herein-described rack comprising the base having the brackets, the roller mounted in said brackets and having the spring to rotate the same in one direction, the drum at one end of the roller, the towel having one end attached to the roller and the soap-suspending cord attached at one end to the drum, said towel and cord being wound when the roller is rotated by the spring and hence caused to move simultaneously and in the same direction.

In testimony whereof I have hereunto set my hand in presence of two subscribing witnesses.

EDWARD P. THOMANDER.
